A. B. PINNEY.
DEVICE FOR ELECTRICALLY CONTROLLING MECHANICAL OPERATION.
APPLICATION FILED JULY 20, 1917.
1,278,743. Patented Sept. 10, 1918.

UNITED STATES PATENT OFFICE.

ARON B. PINNEY, OF NEW YORK, N. Y.

DEVICE FOR ELECTRICALLY CONTROLLING MECHANICAL OPERATION.

1,278,743.

Specification of Letters Patent. Patented Sept. 10, 1918.

Application filed July 20, 1917. Serial No. 181,824.

To all whom it may concern:

Be it known that I, ARON B. PINNEY, of New York, in the county of New York and State of New York, have invented certain new and useful Improvements in Devices for Electrically Controlling Mechanical Operation; and I do hereby declare the following to be a full, clear, and exact description of the invention, such as will enable others skilled in the art to which it appertains to make and use the same.

My invention has particular reference to the operation of quick closing valves for automatic engine stops.

15 In Figure 1 I have shown my improvement attached to a valve. Fig. 2 is a perspective, and Fig. 3 a section.

The valve 1 is or may be of the kind well known commercially for preventing racing or over speeding of stationary engines. As shown it is equipped with a lever 2 formed with hooks 3 adapted to normally engage and hold a weighted valve stem 4. When the lever is raised by the plunger 5 and turns on its fulcrum 6 the hooks disengage the stem 4 and permit the stem to gravitate to quickly close the valve. A weighted lever 6^a is keyed to the shaft 6 on which lever 2 is fulcrumed. This aids the action of the 25 plunger in swinging lever 2 to free the stem 4.

As improved means for actuating the lever 2 I show the following parts: The plunger 5 is movable in a casing 7. A spring 8 is coiled about the plunger and bears against a pin 9 extending through the outer end of the plunger and against a shoulder 10 in the casing 7. A link 12 connects the plunger with a bell crank lever 13, one of its 30 fulcrum points being designated at 13^a and the other at 13^b. The link is formed with a recess 14 to receive the shaft 15 on which the bell crank is mounted when the parts are in the dotted line position of Fig. 3. 35 This shaft is held in the casing 7. A bar 16 on the free arm of the bell crank constitutes an armature to be attracted and held by electro-magnets 17 mounted on the cas-

ing. In this position it will be noted that the fulcrum points 13^a and 13^b and the shaft 50 15 are substantially in alinement but not exactly so, that is, they are close to the center and sufficiently near it to permit the magnet attraction to hold the armature and to maintain the spring retracted. By means of a 55 suitable switch 18 the current normally energizing the electromagnets may be cut off thus permitting the spring pressure to instantly project the plunger and operate the lever 2 to release the valve stem. 60

When it is desired to again place the plunger in its retracted position the armature is turned by hand into engagement with the magnets.

From the foregoing it will be seen that 65 mechanical power is secured and stored by the compression of the spring and that very slight magnetic power in the magnet is necessary to hold the spring retracted while the opening of the circuit energizing the 70 magnets causes the instant release of the plunger. It will also be understood that this electric controlling means is available for various uses and is not necessarily limited to the operation of a valve. 75

I claim as my invention:

1. In a device of the character described, a plunger, means tending to extend said plunger, a bell crank lever, an armature on said lever, a link connecting said plunger 80 with said lever and an electromagnet adapted to attract said armature and hold said plunger retracted.

2. In a device of the character described, a plunger, means tending to extend said 85 plunger, a shaft in line with said plunger, a bell crank lever mounted on said shaft, an armature on said lever, a link connecting said plunger with said lever and formed with a recess to receive said shaft when said 90 plunger is retracted, and an electro-magnet tending to hold said armature and maintain said plunger retracted.

In testimony whereof, I have signed this specification.

ARON B. PINNEY.
